VENTILATED ROTARY BRUSH

Laurits Henrik Nielsen, Kolding, Denmark, assignor to The Osborn Manufacturing Company, Cleveland, Ohio, a corporation of Ohio

Application December 24, 1936, Serial No. 117,601
In Great Britain June 29, 1936

9 Claims. (Cl. 15—181)

Rotary brushes subjected to rapid rotation are rarely worn out by mere abrasion, since the heat generated by the friction of the brush against the work has a detrimental effect on the bristles and causes the latter to break up before they are worn out.

The object of the present invention is to remedy this defect, and the invention consists essentially in providing the brush with a hub adapted to act as a fan for driving a cooling air through the brush.

By this arrangement detrimental heating of the bristles will be effectively obviated.

The air, which enters centrally at one end of the hub, may be driven by centrifugal force either through grooves or through apertures in the brush rings and through the spaces between the bristles or through peripheral apertures at the back of the hub.

Fig. 1 is a face view, with part of one face plate broken away to show interior features;

Fig. 2 is an axial section on the plane 2—2 of Fig. 1, with certain features in elevation;

Fig. 3 is a face view on plane 3—3 of Fig. 2, showing the hub alone with the front plate removed;

Fig. 4 is a view corresponding to Fig. 2 but limited to the brush section rings;

Fig. 5 is a front view corresponding to Fig. 1 but illustrating a modified form;

Fig. 6 is an axial section on the plane 6—6 of Fig. 5;

Fig. 7 is an axial section on plane 7—7 of Fig. 5; and

Fig. 8 is an axial section corresponding to Fig. 6 but showing a modified form.

The brush comprises an assembly of brush rings *d* mounted in juxtaposition between flanges *f* and *g* on a hub *a*. The latter is provided with tapering recesses *b* carried in axial direction and communicating at their deeper ends with the atmosphere through a central aperture *h* in the flange *f*. The brush rings are radially grooved so as to form channels *c* through which the recesses *b* communicate with the spaces between the bristles. The hub parts between the recesses *b* form radial vanes which, when the brush is in operation, induce by centrifugal force an air current which enters the hub through the aperture *h* and passes out through the channels *c* and through the spaces between the bristles *e*. An effective cooling of the brush will thus take place which prevents the deterioration of the bristles.

Instead of leading the air out through the brush rings, it may be discharged through pe-

ripheral apertures at the back of the hub, as in Figs. 5 to 7.

In Figs. 5 to 7 the hub comprises a central axial boss *a'*, spokes *k* radiating therefrom and defining interior recesses *b'*, flanges *f'* and *g'* only one of which happens to be here shown as removable, and brush rings *d'* which preferably are not provided with vent apertures.

The front flange or cover plate *a'* is centrally apertured as at *m* to permit ingress of air surrounding the shaft *n*. The spokes *k* are relieved at their upper ends as at *p'* facilitating inflow of air, in a manner similar to that shown at *p* in Fig. 2. The flange or rear face plate *g'* is perforated with a series of holes *r* disposed well outwardly from the central boss *a'*, whereby centrifugal effect sets up air currents as shown in Fig. 6.

Although the brush sections *d'* are not arranged with radial vents, it will be appreciated that where a greater volume of air flow is necessary or where conditions otherwise make radial escape desirable, the ventilated sections such as *d* of Fig. 2 may be used with the hub of Fig. 5, all as shown in Fig. 8.

Both in the form shown in Fig. 1 and that shown in Fig. 5, the several brush rings or sections, *d* or *d'*, carry inwardly directed lugs *s* to prevent circumferential slipping. The brush rings *d* of Fig. 1 are grooved as at *c* to allow radial discharge of air and are indented as shown at *u* in Fig. 1 or *v* in Fig. 5 to prevent creeping of the bristles.

It will be appreciated by those skilled in the art that modifications of proportions, sizes and arrangement details can be made within the scope of the invention.

Having now particularly described and ascertained the nature of my said invention and in what manner the same is to be performed, I declare that what I claim is:

1. A rotary brush including in combination hub members adapted to act as a fan for driving air through the brush, wherein the hub is provided with recesses which communicate with the atmosphere through a central aperture at one end of the hub and form between them radial vanes operative to drive air by centrifugal force through apertures remote from the axis of rotation.

2. A rotary brush comprising in combination a plurality of side-adjacent turns of metal-channel brush material, a hub whereon said turns are mounted, comprising in combination a plurality of spokes extending from end to end of said hub

and defining air spaces within the brush structure, plates secured to said spokes at each end and holding said turns therebetween, said turns being mounted on the outer faces of said spokes, 5 the inner parts of said spokes being cut away inwardly along the axial length of the hub, a central axial bore through the intersection of said spokes, an edge defining an opening through one end plate at the cut-away of the spokes, said 10 axial bore extending through the other end plate, and openings to the atmosphere from said air spaces peripherally more remote than said inlet opening from the axis of rotation.

3. A rotary brush comprising in combination a plurality of sections, a hub whereon said sections are mounted, said hub including a central boss of approximate conical shape when seen in axial section, a plurality of walls in spoke-like arrangement extending the axial length of said hub, a 20 cover plate at each end of said spoke-like walls, and brush sections supported by the outer faces of said walls, and clamped between said cover plates, with air passages through one of said cover plates.

25 4. A rotary brush comprising in combination a plurality of sections, a hub whereon said sections are mounted, said hub including a central boss of approximate conical shape when seen in axial section, a plurality of walls in spoke-like 30 arrangement extending the axial length of said hub, a cover plate at each end of said spoke-like walls, and brush sections supported by the outer faces of said walls, and clamped between said cover plates, with air passages through one of 35 said cover plates and between said sections.

5. A rotary brush comprising in combination a plurality of circumferential ring-shaped sections, a hub whereon said sections are mounted, said hub comprising in combination a plurality of 40 spokes extending from end to end of said hub, plates secured to said spokes at each end, said brush sections being mounted on the outer faces of said spokes, and inwardly projecting lugs on said sections adapted to engage said spokes.

6. A ventilated rotary brush or the like, comprising in combination a plurality of sections, and a hub whereon said sections are mounted, said hub comprising an axial boss and a plurality of spokes thereon, plates at each end of said spokes covering the spaces between the spokes and preventing axial movement of the sections, an inner edge of one of said plates concentric with the axis defining an opening to the spaces between said spokes, and air passage means in the other of 10 said plates.

7. A ventilated rotary brush or the like, comprising in combination a plurality of sections, and a hub whereon said sections are mounted, said hub comprising an axial boss and a plurality of 15 spokes thereon, plates at each end of said spokes covering the spaces between the spokes and preventing axial movement of the sections, an inner edge of one of said plates concentric with the axis defining an opening to the spaces between 20 said spokes, and air passage means between said sections.

8. A ventilated rotary brush comprising in combination a plurality of sections and a hub, said hub comprising an axial boss and a plurality of 25 of spoke plates springing therefrom, said boss and the inner corners of said spokes being relieved at one end, flange plates at each end of said spokes, a central opening through one of 30 said flange plates at the relieved corners of the spokes, and paraxial openings in the other of said flange plates placed further from the axis than said central opening.

9. A rotary brush including in combination hub members adapted to act as a fan for driving 35 air through the brush, wherein the hub is provided with recesses which communicate with the atmosphere through a central aperture at one end of the hub and form between them radial vanes operative to drive air by centrifugal force 40 through apertures remote from the axis of rotation between the brush channels and through the back of the hub.

LAURITS HENRIK NIELSEN.
